JOSEPH BLONDIN, OF LOS ANGELES, CALIFORNIA

COMPOSITE CONTROL SURFACE FOR AIRPLANES

Application filed January 13, 1930. Serial No. 420,540.

5 My instant invention relates to airplanes which employ wing braces of the inclined strut type, and to a method and means for improving the control of such airplanes, in all attitudes of pitch, roll and yaw, and whereby said means also function as an air-brake to overcome the momentum of the machine as a whole, when landing; hence the terms "universal" and composite function" as applied to 10 this invention.

15 All conventional airplanes employ a hinged, horizontal surface or elevator to control pitch attitudes: two hinged, horizontal surfaces or ailerons to control roll attitudes, and a hinged vertical surface or rudder to control yaw attitudes, and no practical air-brake mechanism has yet been developed, to 20 my knowledge.

25 My present invention, in the form of a pair of simple surface elements, is intended to supplement the functions of all of the separate control elements enumerated above, as well as to provide in a practical form, a braking mechanism for airplanes.

30 This universal or composite function control means comes propitiously at a time when airplanes are being constructed in ever-increasing dimensions. This extension of airplane dimensions involves a corresponding extension of their center of inertia which 35 introduces an artificial or false moment of stability; false, because it exists only while it exists. When any extraneous force (air gusts, etc.) disturbs this false stability, the airplane's extended center of inertia opposes re-establishment of real stability much more than in the case of smaller machines whose center of inertia is made to coincide more closely with their true center of gravity.

40 Present day, tri-motored airplanes carrying wing-engine nacelles and loads, and disposing their passenger loads far to the rear of the machine's center of gravity, and future, multi-passenger airplane designs now under 45 construction in which engine and passenger

loads will be disposed along and within the wing element, are notable cases wherein the machine's center of inertia becomes a menace, instead of a contribution, to the real stability of the ship. The ships in question therefore 50 reach a point in dimensions where their elevator, aileron and rudder surfaces become inadequate because they are forced to act upon a moment-arm measured to the ship's center of inertia instead of its center of gravity, 55 and some added means of intensifying the action of said control surfaces or of supplementing their action becomes necessary in the interest of maneuverability and safety.

It is an object of this invention to provide 60 an auxiliary means to supplement the action of the conventional control elements of airplanes. This means becomes particularly practical in all types of airplanes whose wing element is braced by inclined struts extending 65 between said element and the airplane's fuselage. This invention employs a desired length of the rear set of such struts to serve as posts to which are hinged control surfaces similar to the machine's ailerons and disposed, 70 like the ailerons, one at each side of the machine. Unlike the ailerons, however, these auxiliary control surfaces are disposed to operate independently of each other and upwardly only, being stopped against operation 75 below the plane of the respective strut to which each quasi-aileron surface is hinged. These auxiliary control surfaces are operated in suitable manner, as by the pilot's feet through the medium of a split or divided rudder-bar and appropriate control cables. 80

This same rudder-bar also operates the usual rudder as in conventional types except that the cables operating the rudder are attached thereto by a yielding means, such as a 85 set of tension springs. Thus, operating right rudder-bar will turn the rudder-surface to the right and will simultaneously lift the right dihedral, universal or composite function control surface above the plane of the 90

right-hand rear strut at which position it will derive desired drag and down reactions from the air-stream. This drag reaction is very effective for ruddering because it operates on a material moment-arm back of the machine's center line, and, further, the down reaction will at the same time cause the machine as a whole to bank in the proper attitude for a right turn.

10 Thus, this universal control is much more effective as a turning medium than the conventional rudder-surface alone, which normally lends no assistance towards proper banking of the machine for the turn. During 15 all this operation of right turn and left universal control surface is inoperative and lying in the bed of the wind directly in the plane of the strut to which it is hinged. As a corollary, stepping on left rudder bar will 20 operate the left rudder and left universal control simultaneously, while the right universal control surface remains inoperative. Thus these universal control surfaces become 25 effective and practical auxiliary or supplementary rudders.

Should the airplane as a whole lose lateral stability, rolling toward the right, and requiring aileron action for recovery, the right aileron would be lowered as in conventional 30 practice and the left aileron would be raised.

In such case the pilot would operate the 35 left universal control surface which would rise and thus supplement the action of the left aileron and simultaneously, also, the left rudder would be operated, all these maneuvers co-operating to bring the machine to an even keel and thus these universal control surfaces become effective and practical, auxiliary and supplemental ailerons.

40 With this invention, upon landing the pilot would instinctively push his feet forward (just as an automobile driver does to release clutch and set brakes) and, through the medium of the two-part rudder bar, both universal 45 control surfaces would be made to lift in action simultaneously, introducing a positive braking effect against the air and supplement such other mechanical medium as might be employed. Thus, these universal 50 control surfaces become effective and practical auxiliary brakes. During this braking operation the machine's conventional rudder would remain inactive because of the "give" of the provided springs under the pull, 55 equally, of the rudder cables. Further, since these universal controls are hinged to the rear set of wing struts, which are normally located rearward of the machine's center of gravity, their drag and downward components of air 60 pressure would supplement the action of the rear elevator in holding the machine's tail-skid down in contact with the ground. Wherefore, the universal control surfaces become effective and practical, auxiliary elevators.

A special object is, therefore, to provide, in one control element, auxiliary efforts supplementing the actions of all of the control elements normally used on conventional type airplanes; together with the provision of an 70 entirely new brake function designed to facilitate and shorten the length of run of the airplane on the ground when landing.

The invention consists of certain advancements in this art as set forth in the enclosing 75 disclosure and having, with the above, additional objects and advantages, and whose construction, combination and details of means, and the manner of operation will be made manifest in the description of the here-with illustrative apparatus; it being understood 80 that modifications, variations and adaptations may be resorted to within the scope, principle and spirit of the invention as it is more directly claimed hereinafter.

85 Figure 1 is a bottom plan of an airplane showing the location of the universal control surfaces.

Figure 2 is a front elevation showing the 90 universal control surfaces in elevated position for conjunctive action to serve as air-brakes.

Figure 3 shows in detail the divided rudder-bar mechanism and the control cables employed to operate the composite-function 95 surfaces.

The assembly includes a conventional type monoplane with a fuselage A, wings B, tail C, fin D, elevator E and rudder F, ailerons G and G', running gear H, and dihedral struts 100 I and I', and J and J'. Hinged to the latter are the two universal or composite-function control surfaces K and K' which are designed to operate upward only, as shown in Fig. 2, being restrained from any movement below 105 the plane of the respective struts J and J' by respective rests L and L'.

Fig. 3 illustrates the independent rudder-bar arms M and M' which operate the vertical rudder F, through the medium of the cable 110 tensioning springs O and O'. When the rudder bars are operated in conjunction these springs permit the concurrent give of the cables N and N' without affecting the angular position of the rudder proper.

When one rudder bar, as arm M, is operated alone the rudder proper will be actuated by the cable N, not positively, as in conventional practice, but yieldingly against the tension of the springs O and O', while at the 115 same time the cable P will serve to pull up the control surface K which is thus made co-operative by its drag and banking effects with the rudder F, in steering the airplane to the right. During this operation the rudder bar 120 arm M' remains inactive, in neutral position, and therefore control surface K' remains seated on its rests, such as rods L'. Similarly, when right joy stick is operated to bank 125 the airplane to the right through the medium 130

of the conventional ailerons G and G' right rudder bar M would be operated to effect the action of the universal control surface K and this would co-operate with the aileron G in banking the airplane to the right, aided 5 simultaneously by the drag of surface K and the turning couple introduced by the rudder F, to steer the airplane as a whole to the right.

What is claimed is:

0 1. In airplane controls, auxiliary independent control surfaces hinged to conventional inclined struts as carrier parts and which are each provided with an independent rudder bar member, and a rudder actuated by either member.

2. In airplane controls, a right hand and a left hand supplemented aileron surface for braking function in flight by air resistance and hinged to relative dihedral wing struts 20 and operated independently, by transmission means in conjunction with and auxiliary to the action of the usual rudder surfaces.

3. An airplane having, in combination, a steering rudder, and a system of air brake 25 surfaces co-operatively combined with the rudder, and means for operating either brake surface and the rudder irrespective of the other surface, said means having only an upward positive action on said surfaces.

30 4. An airplane having, in combination, a steering rudder, a pair of air resistance braking surfaces to reduce speed of ship before and after landing and operating means connecting the said surfaces and the rudder and positively moving said surfaces in one direction only.

40 5. An airplane having, in combination, a steering rudder, a pair of right and left air resistance braking surfaces, and means providing for the operation of both surfaces to set them against the air simultaneously without effect on the rudder and connecting them thereto.

45 6. An airplane having, in combination, a rudder, a pair of right and left hand air resistance braking surfaces which are operatively attached to respective dihedral wing struts of the airplane, and selective operating means connecting the brake surfaces and the rudder for concurrently producing right rudder or left rudder and respective action of the relative brake surface and for actuating the said surfaces without action of the rudder, and means on the struts for stopping the 55 free brake surfaces in the bed of the wind.

60 7. An airplane having rudder, aileron and elevator surfaces, and supplemental brake, rudder and quasi-aileron means consisting of a set of right and left auxiliary control surfaces mounted on dihedral struts, and means for operating said auxiliaries upward together as brakes and "spoilers", or to operate either as down-effect ailerons and also with 65 rudder effect while the other drags idle in the

air stream; each auxiliary surface having an operative connection with the main rudder and being operative therewith only when the rudder is turned toward the relative side on which the acting auxiliary is disposed; the auxiliaries being movable upward only by said means and having limited downward movement; said rudder connection having a compensating device to allow rudder movement after limit movement of either auxiliary surface. 70 75
